UNITED STATES PATENT OFFICE.

PASQUALE VIOLENTE, OF GALLERIA VITTORIA, NAPLES, ITALY.

DEVICE FOR CUTTING OUT WOMEN'S GARMENTS.

Application filed May 26, 1921. Serial No. 472,806.

To all whom it may concern:

Be it known that I, PASQUALE VIOLENTE, a subject of the King of Italy, and residing at Galleria Vittoria, Naples, Italy, have invented certain new and useful Improvements in Devices for Cutting Out Women's Garments, of which the following is a specification.

The invention relates to a device adapted to be used for cutting out women's garments of any kind and the device is constructed and arranged so that it may be set in accordance with the measures taken on the person, when it will automatically define the lines 15 to be drawn on the cloth for cutting out the garment.

Up to now the operations for cutting out women's garments required a series of calculations on the measures taken on the person and the patterns had first of all to be cut out on paper and then to be copied on the cloth, which was conducive to a great loss of time and required in any case the work of a person experienced in the art.

It has already been proposed to construct apparatus intended to avoid the drawbacks of the known methods for cutting out women's garments, but these apparatus had to be applied to the body of the person whose 30 measures had to be taken and a model of the garment had to be shaped on the person; the results obtained however have not been satisfactory.

The device according to the invention is based on a quite different principle. According to the invention, measures are taken on the person by hand as heretofore and these measures of which only a quite limited number are required with this method, are 40 used to adjust the device which will then show the lines that must be followed for cutting out the component parts of the garment.

The device according to the invention comprises a series of straight and of curved arms 45 or levers which are slidable in a longitudinal direction respecting a central or body part on which they are mounted, this sliding motion being imparted to them preferably by means of gears carried by the said central 50 or body part. The slidable arms or levers carry suitably shaped templates intended to define the lines to be followed for the cutting operations. When the gears are turned, the slidable arms or levers in engagement 55 therewith are brought to slide forward or backward on the central or body part so that

the lines defined by the templates will be shaped in accordance with the extent to which the gears have been rotated. As the rotary movements of the gears are made 60 dependent on the measures taken on the person, it is evident that the lines set up by the various templates will vary in accordance with these measures and they may thus be used for tracing out the component parts of 65 a well-fitting garment on the cloth.

In order that the invention may be readily understood, the same will be described with reference to the accompanying drawings, which shows a device that may be used for 70 cutting skirts, jackets and other like garments. In these drawings—

Fig. 1 is an upper plan view of the device,

Fig. 2 is a part rear view showing the 75 upper arms or levers with the respective gears, but without the templates,

Fig. 3 is a similar view of the lower arms also without the templates and with their gears, while

Fig. 4 shows an example of the lines which may be defined by the apparatus for cutting operations.

Fig. 5 shows a guide piece for the rack arms to hold them in mesh with the pinions. 85

Fig. 6 shows on a larger scale the connection between some of the arms and the templates,

Fig. 7 is a schematic view of the control mechanism.

The device shown in the drawing comprises a plurality of arms or levers indicated with the letters from *a* to *h* and *l* to *q*, which are all mounted on a central body member *A* and are slidable thereon in a 95 longitudinal direction. Some of these arms or levers are straight and will therefore move along a straight line, while others are curved and will thus describe an arc on being moved. All the arms or levers are 100 of rack formation on one side as shown in *r* and these racks engage with pinions carried by the body member *A* the rack arms being arranged in slotted guides (Figure 5) secured to the central or body member *A*, 105 so as to be held in mesh with their respective gears with which they are held in engagement by means of the straps *w* and the springs *x*. Of course, instead of rack and pinion gears other suitable means may be 110 employed to impart a sliding motion to the arms or levers.

The pinions are rotated, for example, by means of a key intended to be applied to the shaft B of the driving pinion F of a train of gears for the upper set of arms or levers and successively to the shaft C of the driving pinion G of the trains of gears for the lower set of arms or levers, as is indicated in figure 7, or arrangements may be made to rotate both trains of gears simultaneously to cause the arms or levers to move respecting the central or body part.

The movements of the upper and lower set of gears may be controlled, for example, by means of two indicating devices D, E, marked with numbers and connected, for example, with wheels H, I on the shafts of the driving pinions, these indicating devices showing in the constructional form here illustrated one the measures of the chest and the other those of the waist to which the positions of the arms or levers respectively correspond.

A cover plate K is provided at the base of the device and has the shaft B rotatably mounted on it.

Each of the arms carries one or more templates s_a, s_b, s_c and so on, which in some cases are interconnected by spiral springs as shown, and these templates define each a part of one of the lines to be followed for the cutting operations, the templates being suitably shaped for this purpose and they are interchangeable so as to adapt them to the various fashions or ways in which the garments are to be cut. In order to be able to adjust the device, these templates are slidably arranged on the arms or levers, a suitable interconnection being obtained, for example, by a slot as shown in t , and the templates may be secured in their adjusted position by the aid of pressure screws such as shown in Figure 6 or the like.

In order that the device should be able to take care of any deformities or irregularities of the body, the arms n, o are not provided with the usual straight slots t , but these arms are enlarged towards their outer end and a curved slot is formed therein which allows the respective templates being displaced in accordance with these deformities. For the same purpose, the arms c and d are provided with cross-shaped slots (Figure 6) which allow the templates being displaced in cross-wise directions.

The lines to be followed for cutting out a garment are defined by combinations of the outlines of two or more templates, while the brief intervening spaces between the templates may easily be filled in by hand, as it will be readily understood. For each number shown by the indicating device a different series of lines will be obtained and all the component parts of a garment may thus be suitably outlined by the device and be reproduced on the cloth.

The device will be used in the following way.

The apparatus here illustrated requires only two measures being taken on the person, one over the breast and the second one round the waist. The first indicating device D refers to the breast measures, the second one E to the waist measures. After having taken the measures, the apparatus will be operated by means of the key until the first indicating device has reached the number of the breast measure and the second one that of the waist measure. When these numbers have been reached, all the arms or levers will have been displaced to such an extent that the templates define the lines to be followed for cutting out a garment corresponding with the two measures taken on the person.

For example, the templates $s_a, s_b, s_c, s_t, s_q, s_p$ define the full line I in Fig. 4, which corresponds to the front part of the garment to be cut, the templates s_o, s_n, s_m, s_l define the full line II which corresponds to the rear part, the templates s_p, s_o together with the templates s_n, s_l define the dotted line III for the part above the sleeve, and so on. In the constructional form shown a part of the line for a décolletage is always indicated by the recessed pieces u, v secured on the central part.

It is evident that when the keys are operated so as to bring new numbers in view on the indicating devices, all the templates will be displaced and thus all the lines will be altered to correspond now with the new breast and waist measures. The relation between the various transmissions and between the successive movements of the arms or levers and of the templates will be calculated so as to correspond to the measurements of a person of regular build, and for such a person the operation of the key is sufficient to bring all the templates in the required position for defining a well fitting garment, while any deformities are taken care of in the way above described. The shape of the templates, the size of the gears, the curvature of the curved arms and all the other particulars are further calculated in accordance with the rules of fashion. But it is possible to cut with the aid of the same apparatus garments of different kind, for instance both long jackets and blouses. For this latter purpose, the lower templates are all jointed at z and the line which connects these joints z represents the waist line IV (Fig. 4) of the garment, so that by prolonging the lines to a larger or smaller extent below this waist line, jackets or blouses of different length may be outlined.

It will be evident that the device is here illustrated only by way of example and that various modifications may be made therein without departing from the spirit of the in-

vention. For example, the number of the arms and templates may be increased or diminished according to requirements, or the apparatus may require more than two 5 measures to be taken on the person, and so on.

What I claim is:

Apparatus for cutting women's garments comprising a central or body member, a plurality of arms arranged on the body member, these arms being some straight and some curved and all of rack formation on one side, trains of gears arranged to be operated from a shaft or shafts extending 15 through the body member, and in engage-

ment with the racks, indicating devices controlled from the said shaft or shafts, interchangeable templates on the arms or levers to define the lines to be followed for the cutting operations when the arms or levers 20 are displaced respectively along straight or curved lines through the operation of the gears.

In testimony whereof I have signed at Naples this 27th day of April, in the presence of two subscribing witnesses.

PASQUALE VIOLANTE.
